UNITED STATES PATENT OFFICE.

WARREN S. BELDING, OF CHICAGO, ILLINOIS.

ARMATURE-CORE FOR DYNAMO-ELECTRIC MACHINERY.

SPECIFICATION forming part of Letters Patent No. 394,905, dated December 18, 1888.

Application filed January 24, 1888. Serial No. 261,779. (No model.)

To all whom it may concern:

Be it known that I, WARREN S. BELDING, a citizen of the United States, residing at Chicago, in the county of Cook and State of Illinois, have invented certain new and useful Improvements in Blanks for Building Armatures; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to a blank for building armatures for dynamo-electric machines and electric motors.

The object of the invention is to produce a blank with which may be built interlocking 20 segments or sections of an armature, which sections when combined shall form an armature which is symmetrical throughout. The blank is cut in thin strips from sheets of material, and a number of them are united to 25 form a section or segment of the armature, and two or more sections are interlocked at their meeting ends to constitute the armature.

Referring to the accompanying drawings, 30 Figure 1 is a view of two of the blanks, one turned to the right and the other to the left. Fig. 2 is a view of said two blanks, one placed upon the other. Fig. 3 shows a rack used in building up the blanks with the 35 blanks for one section of the armature upon it. Fig. 4 shows two sections forming halves of the armature, one being partially wound, and dotted lines indicating how they are to be further wound. Fig. 5 shows two of the 40 blanks of another form. Fig. 6 shows said two blanks lying one upon the other. Fig. 7 shows two segments forming the halves of an armature built of the modified form of blank. Fig. 8 is a cross-section in line *x-x* of Fig. 7. 45 Fig. 9 is a section through the interlocked meeting ends of the segments after they have been united by a bolt.

An inspection of Fig. 1 will disclose a blank, which is the half of a circle, and which is divided into spaces by four equidistant holes, A, leaving between them the equal spaces B, and leaving at one end a short space, B', and

at the other end a longer space, B², the sum of which last-named spaces is equal to one of the spaces B. The spaces B occupy a little 55 more than the segment-spaces of the armature, which are to be covered by the coils of wire. For the purposes of description I shall designate said spaces to be covered by the coils as the "bobbin-spaces." The space B² 60 is so much shorter than the spaces B as to cause it to terminate opposite the adjacent hole coincident with the bobbin-space. The opposite end of the blank terminates at said bobbin-space. It may be said that this blank 65 is unsymmetrical. Although the holes A are equidistant from each other, no two are equidistant from the center of the blank or from its ends. In other words, the group of holes is shifted laterally from one end of the blank 70 toward the other. If two of the blanks are brought together with their dissimilar ends meeting, B' meeting B², a complete circle is formed, and said circle is divided by eight 75 equidistant holes into eight equal spaces, B and B' B².

For convenience in description I designate the holes A by the serial numbers 1 2 3 4, beginning with the hole next B', and the spaces B by the serial numbers 1 2 3, beginning next 80 B'. Now if the two blanks be laid upon each other, with similar ends in opposite directions and the hole 4 of the upper blank placed directly over hole 1 of the lower blank, then holes 3, 2, and 1 of the upper blank will be 85 directly over holes 2, 3, and 4 of the lower blank. The spaces 1 2 3 of the upper blank will then lie over the spaces 3 2 1, respectively, of the lower blank, each of the spaces B² being partially covered by the spaces B', the remainder of each of said spaces B² being uncovered. Said uncovered part is equal to and coincident with the bobbin-space of that part of the circle in the finished armature. In other words, it occupies one of the segmental 95 spaces to be covered by the coil. If we now apply upon the upper blank one that is reversed with reference to said upper blank and corresponds in position to said lower blank, and then place upon this third blank a fourth 100 corresponding to the second, we have a sufficient number of blanks to complete one-half of an armature, and the number of blanks may be further increased indefinitely. Pins

or bolts may be passed through the holes A to hold the blanks together during the operation of winding. The bobbin-spaces between the holes may now be wound.

- 5 At each end of the half of the armature spaces will be left between the parts B². In bringing the ends of the halves of the armature together to form a complete circle the parts B² of one-half of the armature pass into 10 the spaces between the parts B² of the adjacent end of the other half of the armature, and the two blanks forming the same circle lie in the same plane and abut. When the two halves of the armature have been thus 15 united, it will be seen that the parts B² have formed two bobbin-spaces which are not yet wound with coils. These must then be wound by passing the wire through the armature; but the blanks may be so combined as to 20 make all the bobbin-spaces complete before the two halves of the armature are united. All bobbin-spaces may, therefore, be wound before the halves of the armature are united. Upon this point attention is directed to Figs. 25 5 and 6. In said figures the holes 4, 3, and 2 of the upper blank are placed over holes 2, 3, and 4, respectively, of the lower blank. This brings the parts B² against spaces B and leaves the portions B' and an equal portion 30 of the adjacent spaces B uncovered. Blanks of the form shown in Fig. 1 may be applied to each other in this way. (See Fig. 4.)
- The total of the uncovered ends of the blanks 35 constitute the parts that interlock, and they are between two bobbin-spaces in the finished armature. The portions of the armature between the bobbin-spaces are the holes. In Figs. 5, 6, and 7 the poles are extended outwardly and the extension designated by the 40 letter C. Each of said extensions of the poles is pierced by a hole, C', the purpose of which is, first, to form a pole in the finished armature of relatively large surface and small mass; second, to form an opening through the pole 45 to afford ventilation, and thereby prevent heating. This feature will be further considered in another application for Letters Patent to be filed by me.

The operation of building up the blanks to 50 form one-half of an armature may be facilitated by using a device having two upright posts, D D, rising from a base, E, said posts being set from each other a distance equal to the distance between two of the holes A A, 55 and being passed, for example, through holes 2 and 4 of one blank and through 4 and 2 of the next, and again through 2 and 4 of the next, and so on. When the blanks have been thus built up, bolts or pins F may be temporarily 60 passed through the holes A to bind said blanks together until the coils G have been wound about the bobbin-spaces. By this arrangement of the plates the holes are brought over each other in the intermeshing poles or 65 ends of the two halves of the armatures. Bolts H may be passed through these holes to secure said ends, as shown in Fig. 9.

As already explained, the holes A are equidistant and pass through the poles. The poles are therefore also equidistant. All the poles 70 of the entire circle may therefore be equally distributed and of equal size; and it follows, also, that all the bobbin-spaces of the entire circle are equally distributed and of equal dimensions. The holes A being located in the 75 poles are not covered by the coils. Consequently the bolts or pins F uniting the blanks during the process of winding may be removed after the winding has been accomplished and used again. Another advantage 80 resulting from not covering the holes A by the winding is that they afford ventilation in the finished armature. Being formed in the poles, said holes A reduce the mass of material in the poles, whereby the magnetic effect 85 in the remaining mass is intensified.

The holes, the poles, and the bobbin-spaces being thus respectively equal in distribution and dimensions, it results that there is a strictly even distribution of weight, pole-surface, and coils throughout the armature, and there is produced the highest possible degree 90 of regularity of current and smoothness of motion. A portion or all of the holes A and C are also to be used to receive bolts or other 95 devices to secure the armature, through the medium of a spider, to the shaft upon which the armature is mounted. Said bolts may, however, be of less diameter than said holes A or C, in order that they may not fill all of 100 said holes, but leave them partially open for ventilation. In other words, the blank is to be cut with the holes larger than the bolts to be used, for the purpose above mentioned.

The winding of the armature may be much 105 more rapidly done before the two halves are united. When the armature is a full circle, the winding must be done by passing the wire through the armature on a shuttle. If the separate halves are wound, they may be treated 110 like spools—namely, by rotating them to take the wire.

The blanks may, obviously, be thirds or 115 quarters or other divisions of a complete circle, provided they be so spaced as to build up 120 with their ends abutting and form full and equal bobbin-spaces and poles.

The blanks are to be cut out of sheets of material, as already stated. This I intend to do by means of dies.

The claims hereto appended are to be understood to apply to the plates herein described and not to the armature. The armature is embodied in an application filed by me February 2, 1888, Serial No. 262,765.

I claim as my invention—

1. A sheet-blank constituting a segment of a circle and divided into bobbin-spaces and poles, which are respectively equal in dimensions and equidistant from each other and located unsymmetrically on said blank, so that there is a bobbin-space at one end of the blank and a pole at the other end, substantially as shown and described.

2. A sheet-blank constituting a segment of a circle and divided into bobbin-spaces and poles which are respectively equal in dimensions and equidistant from each other and located unsymmetrically on said blank, so that there is a bobbin-space at one end of the blank and a pole at the other end, and having formed in each of said poles a hole, A, for receiving pins or bolts, for affording ventilation, and reducing the mass of the pole, substantially as shown and described.
3. A blank forming part of a circle and having equidistant poles with extensions C of equal dimensions, said poles being located unsymmetrically on said blank, so that there is a bobbin-space at one end of the blank and a pole at the other end, substantially as shown and described.
4. A blank forming part of a circle and having equidistant poles with extensions C of equal dimensions, and said extensions provided with holes C', whereby ventilation is afforded and the mass of said pole is diminished, substantially as shown and described.
5. A sheet-blank constituting a segment of a circle and divided into bobbin-spaces and poles which are respectively equal in dimensions and equidistant from each other and located unsymmetrically on said blank, so that there is a bobbin-space at one end of the blank and a pole at the other, and each of said poles

being provided with an outward extension, C, substantially as shown and described.

6. A sheet-blank constituting a segment of a circle and divided into bobbin-spaces and poles which are respectively equal in dimensions and equidistant from each other and located unsymmetrically on said blank, so that there is a bobbin-space at one end of the blank and a pole at the other, and each of said poles being provided with an outward extension, C, and each such extension having formed in it a hole, C', substantially as shown and described.
7. A sheet-blank constituting a segment of a circle and divided into bobbin-spaces and poles which are respectively equal in dimensions and equidistant from each other and located unsymmetrically on said blank, so that there is a bobbin-space at one end of the blank and a pole at the other end, and having formed in each of said poles a hole, A, and each of said poles having an outward extension, and each of said outward extensions being provided with a hole, C', substantially as and for the purposes herein set forth.

In testimony whereof I affix my signature in presence of two witnesses.

WARREN S. BELDING.
